CLAIM

The ornamental design for a skate odometer, as shown and described.

DESCRIPTION

FIG. 1 is a perspective view of the skate odometer embodying the design of the present invention;

FIG. 2 is a front elevational view thereof;

FIG. 3 is a rear elevational view thereof;

FIG. 4 is a side elevational view thereof, the opposite side elevational view being identical thereto; and,

FIG. 5 is a top plan view thereof, the opposite bottom plan view being identical thereto.

The broken line showing of a roller skate is for illustrative purposes only and forms no part of the claimed design.
